UNITED STATES PATENT OFFICE

2,475,507

LIFT MECHANISM

Thorvald Madland, Chicago, Ill., assignor to The Youngstown Steel Door Company, Cleveland, Ohio, a corporation of Ohio

Application January 8, 1946, Serial No. 639,755

12 Claims. (Cl. 16—99)

1

This invention relates to lift mechanism and more particularly to lift mechanism for sliding doors of railway house cars.

It is an object of this invention to provide lift mechanism for sliding doors for railway house cars which shall embody relatively few simple and inexpensive parts, obtain a substantial reduction in the number of castings required, be easily operable in either direction in a plane parallel to the doors, and secure a reduction of the outward projection relative to the doors so that the mechanism may be utilized on cars of varying widths without encroaching on the tunnel clearance.

A further object is to provide such mechanism embodying an actuating lever which shall be maintained in the vertical position except when the door is being opened or closed.

A further object is to provide such mechanism embodying an actuating lever and capable of preventing whipping of the lever when the door is forced upwardly by vibration or impact upon the car.

A further object is to provide lift mechanism for sliding car doors which shall embody connecting bars, springs and abutments for the springs associated with the bars so as to prevent transverse bending thereof.

A further object is to provide lift mechanism for sliding car doors which shall embody connecting bars, springs and abutments for the springs associated with the bars so as to retain the mechanism upon the doors during its assembly with the doors.

A further object is to provide such mechanism embodying rollers and related lifting abutments wherein the lift mechanism is so designed and constructed that impact of the abutments upon the rollers is prevented when the doors drop upon their supporting tracks.

Other objects of the invention will become clear as the description thereof proceeds.

In the drawings forming part of this specification:

Fig. 1 is an elevation of a lower portion of a sliding lift door embodying the instant invention, parts being broken away to illustrate the invention more clearly and on a larger scale.

Fig. 2 is a horizontal section taken on line 2—2 of Fig. 1.

Fig. 3 is an enlarged detail of the outer end of the connecting bars of the lift mechanism.

In the drawings the lift mechanism embodying the instant invention is illustrated upon an outside sliding car door 10 whose panel 11 is

2

formed with spaced horizontal corrugations 12. The lower edge of the door is preferably in the form of a box section which as illustrated comprises the panel 11, a backing plate 13 secured thereto in the inner plane of the panel as by means of rivets 14 and a substantially Z-shaped plate 15 secured to the panel 11 in the outer plane thereof as by means of rivets 16 and extending downwardly therefrom and formed into a web 17 adapted to support the door upon a track 18 and a depending flange 19 lying behind the track so as to prevent disengagement of the door from the car. The lower edge of the backing plate 13 is secured to the latter flange of the Z-shaped plate member 15 in any desired manner. The particular construction at the bottom edge of the door briefly described above forms no specific part of the instant invention except insofar as it provides space for the reception of the lifting mechanism embodying the instant invention. Any desired construction of box section may be utilized or any other construction which will permit operation of the lift mechanism. For example, the box section illustrated in the patent to Beauchamp, 2,373,447, granted April 10, 1945, may be utilized if desired.

Lift mechanism embodying the instant invention is an improvement upon the lift mechanism illustrated in the Beauchamp patent above identified. The instant lift mechanism embodies a plurality of vertically spaced rollers 20 and 21 which are rotatably mounted upon pins 22 and 23 supported in a yoke member 24. One end of a connecting bar 25 is secured to the yoke member 24 as by means of rivets 26. The other end of the connecting bar is pivotally connected as indicated at 27 to an actuating member 28 which is provided with trunnions journaled in the bottom plate 15 and in a bracket member 29. The construction of the actuating member 28, its pivotal securing to the connecting bar 25, and the structure of the bracket member 29 are more specifically detailed in the patent to Beauchamp 2,373,447. An operating lever 30 is mounted upon the outer trunnion of the actuating member.

The lift mechanism also embodies a plurality of similar rollers 31 and 32 disposed on the opposite side of the actuating member 28 and rotatably mounted upon pins 33 and 34 supported in a yoke member 35. One end of a connecting bar 36 is secured to the yoke 35 as by means of rivets 37 and the other end of the bar is pivotally secured to the actuating member 28.

Angle members 38 and 39 are secured as by means of riveting to the formed Z-plate 15. The

inwardly extending legs 40 and 41 of the angle members are slotted as indicated at 42 and 43 in order to receive the connecting bars 25 and 36. By this construction transverse bowing of the connecting bars is prevented and the lift mechanism is securely retained upon the Z-shaped plate 15 during the assembly thereof with the remainder of the door.

The instant invention disposes and maintains the operating lever 30 in a vertical position and prevents whipping of the lever during transit of the cars. To this end the connecting bars 25 and 36 are slotted as indicated at 44 to provide aligned flanges 45 and 46. Coiled compression springs 47 and 48 are mounted upon the aligned flanges 45 and 46. These springs are placed under initial compression with one end abutting the yoke members or the connecting bars and the other end abutting the angle members 40 and 41. In this manner the vertical position of the lever is obtained and whipping thereof is avoided regardless of the normal tolerances and discrepancies of construction. In lowered position the door is frictionally supported upon the track 18 upon which the lower rollers 20 and 31 rest. The upper rollers are disposed under oppositely inclined flanges 49 and 50 formed respectively on angle members 51 and 52 which are secured in any desired manner to the Z-shaped plate 15. Movement of the door along the track is obtained by swinging of the operating lever 30 in the direction in which it is desired to move the door. Swinging of the operating lever which is guided by means of a retaining flange 53 formed on a bracket 54 secured to the door imparts rotation to the actuating member 28. The actuating member through its pivotal connection with the bars 25 and 36 exerts a pull upon these bars in opposition to the springs 47 and 48 which are further compressed. The movement of the bars 25 and 36 causes the rollers 20 and 31 to roll toward each other upon the track 18 and the rollers 21 and 32 to engage and roll along the underside of the inclined flanges 49 and 50. The movement of the rollers imparts a lifting force to the door which is accordingly raised above the track whereupon the door is supported upon the rollers for movement along the track. Upon release of the operating lever the door automatically seats itself upon the track and establishes frictional engagement therewith so that the track instead of the rollers carries the weight of the door.

It is apparent that the action of the springs 47 and 48 constantly biases the rollers away from each other as long as no external force is applied to the operating lever. The lever is accordingly maintained in its vertical position. Moreover, should the door rise relative to the track as a result of vibration or impact to the car, the springs effectively maintain the vertical position of the operating lever. Since the action of the springs maintains the plurality of rollers in the position illustrated in the drawings, it is apparent that when the door again drops upon the track impact between the inclined flanges 49 and 50 and the rollers 21 and 32 will be prevented and the impact will be entirely upon the track.

It will be apparent that numerous changes and modifications in the details of the invention will be clear to those skilled in the art. For example, a single spring may be used in place of the plurality of springs if desired. It is intended, therefore, that all such changes and modifica-

tions be comprehended within this invention which is to be limited only by the scope of the claims appended hereto.

I claim:

1. Lift mechanism for sliding car doors comprising spaced pairs of rollers, means carrying each pair of rollers, an actuating device adapted to be journalled in a said door, said device being pivotally connected with each of said means, members secured to said door on opposite sides of said device, slots in said members through which said means extend, each of said means being coped to provide spaced aligned flanges, compression springs mounted on said flanges, said springs bearing against said means and said members, oppositely inclined members secured to said door, certain of said rollers being engageable with the underside of said inclined members, and a vertically disposed lever mounted on said actuating device.

2. Lift mechanism for sliding car doors comprising spaced pairs of rollers, means carrying each pair of rollers, an actuating device adapted to be journalled in a said door, said device being pivotally connected with each of said means, members secured to said door on opposite sides of said device, slots in said members through which said means extend, springs engaging said members and said roller carrying means, oppositely inclined members secured to said door, certain of said rollers being engageable with the underside of said inclined members, and a vertically disposed lever mounted on said actuating device.

3. Lift mechanism for sliding car doors comprising spaced pairs of rollers, means carrying each pair of rollers, an actuating device adapted to be journalled in a said door, said device being pivotally connected with each of said means, members secured to said door on opposite sides of said device, slots in said members through which said means extend, resilient elements bearing against said means and said members, said resilient elements being under initial compression, oppositely inclined members secured to said door, certain of said rollers being engageable with the underside of said inclined members, and a vertically disposed lever mounted on said actuating device.

4. Lift mechanism for sliding car doors comprising spaced pairs of rollers, means carrying each pair of rollers, an actuating device adapted to be journalled in a said door, said device being pivotally connected with each of said means, abutments secured to said door on opposite sides of said device, each of said means being coped to provide spaced aligned flanges, compression springs mounted on said flanges, said springs bearing against said means and said abutments, oppositely inclined members secured to said door, certain of said rollers being engageable with the underside of said inclined members, and a vertically disposed lever mounted on said actuating device.

5. Lift mechanism for sliding car doors comprising spaced pairs of rollers, means carrying each pair of rollers, an actuating device adapted to be journalled in a said door, said device being pivotally connected with each of said means, abutments secured to said door on opposite sides of said device, compression springs bearing against said means and said abutments, oppositely inclined members secured to said door, certain of said rollers being engageable with the underside of said inclined members, and a ver-

tically disposed lever mounted on said actuating device.

6. Lift mechanism for sliding car doors, comprising spaced pairs of rollers, means carrying each pair of rollers, an actuating device adapted to be journalled in a said door, said device being pivotally connected with each of said means, members secured to said door on opposite sides of said device in transversely overlapping relationship with said means, each of said means being coped to provide spaced aligned flanges, compression springs mounted on said flanges, said spring bearing against said means and said members, oppositely inclined members secured to said door, certain of said rollers being engageable with the underside of said inclined members, and a vertically disposed lever mounted on said actuating device.

7. Lift mechanism for sliding car doors comprising spaced pairs of rollers, means carrying each pair of rollers, an actuating device adapted to be journalled in a said door, said device being pivotally connected with each of said means, members secured to said door on opposite sides of said device in transversely overlapping relationship with said means, resilient elements bearing against said means and said members, said resilient elements being under initial compression, oppositely inclined members secured to said door, certain of said rollers being engageable with the underside of said inclined members, and a lever mounted on said actuating device.

8. Lift mechanism for sliding car doors comprising spaced pairs of rollers, means carrying each pair of rollers, an actuating device adapted to be journalled in a said door, said device being pivotally connected with each of said means, members secured to said door on opposite sides of said device in transversely overlapping relationship with said means, springs engaging said members and said roller carrying means, oppositely inclined members secured to said door, certain of said rollers being engageable with the underside of said inclined members, and a vertically disposed lever mounted on said actuating device.

9. Lift mechanism for sliding car doors comprising spaced pairs of rollers, means carrying said rollers, a lever mounted on said door for swinging movement in a plane parallel thereto, said lever being operatively engaged with said roller carrying means, members secured to said door on opposite sides of said lever, flanges on

said means, compression springs mounted on said flanges and bearing against said means and said members, and inclined members secured to said door, certain of said rollers being engageable with the underside of said inclined members, for the purpose set forth.

10. Lift mechanism for sliding car doors comprising spaced pairs of rollers, means carrying each pair of rollers, an actuating device adapted to be journalled in a said door, said device being pivotally connected with each of said means, an abutment member secured to said door, a compression spring bearing against said abutment member and the means carrying a pair of rollers, oppositely inclined members secured to said door, certain of said rollers being engageable with the underside of said inclined members, and a vertically disposed lever mounted on said actuating device.

11. Lift mechanism for sliding car doors comprising spaced pairs of rollers, means carrying said rollers, a lever mounted on said door for swinging movement in a plane parallel thereto, said lever being operatively engaged with said roller carrying means, a member secured to said door, a spring engaging said member and said roller carrying means, and inclined members secured to said door, certain of said rollers being engageable with the underside of said inclined members, for the purpose set forth.

12. Lift mechanism for sliding car doors comprising spaced pairs of rollers, means carrying said rollers, a lever mounted on said door for swinging movement in a plane parallel thereto, said lever being operatively engaged with said roller carrying means, a member secured to said door in transversely overlapping relationship with said means, a spring engaging said member and said roller carrying means, and inclined members secured to said door, certain of said rollers being engageable with the underside of said inclined members, for the purpose set forth.
